BASEBALL GAME

Joseph C. Mayer, Cleveland, Ohio

Application May 12, 1933, Serial No. 670,624

3 Claims. (Cl. 273—90)

This invention relates to a game apparatus and more particularly to a baseball game.

Many types of baseball games have been proposed heretofore but in those games of which I have knowledge the particular manner of playing such games depends more or less upon chance and not upon the particular skill of those playing the game, particularly in view of the fact that such games are either played through the medium of a mechanical device or played by throwing dice, spinning a top or some such device.

One of the objects of the present invention is to provide a baseball game of a new type in which the manner of play depends upon the skill of the players.

Another object is to provide an improved baseball game of such construction and which is played in such manner that the players are actively engaged during the progress of the game, and in which many of the rules of the real game of baseball may be utilized and plays made to represent the actual plays in a game of baseball.

A further object is to provide a baseball game of such construction that considerable skill is required to play it and in which the players may obtain considerable exercise.

With the above and other objects in view, which will be apparent from the following detailed description, the present invention consists in certain features of construction and combinations of parts which will be readily understood by those skilled in the art to which the invention appertains.

In the drawing, which illustrates a suitable embodiment of the invention,

Figure 1 is a plan view of the game apparatus of the present invention;

Fig. 2 is a longitudinal section taken approximately on the line 2—2 of Fig. 1;

Fig. 3 is an enlarged section taken approximately on the line 3—3 of Fig. 1 showing one of the cages in front elevation;

Fig. 4 is a section taken approximately on the line 4—4 of Fig. 3;

Fig. 5 is a section taken approximately on the line 5—5 of Fig. 3;

Fig. 6 is an enlarged fragmentary section taken approximately on the line 6—6 of Fig. 1 showing the play cages in front elevation; and

Fig. 7 is a section taken approximately on the line 7—7 of Fig. 1;

Referring to the accompanying drawing in which like numerals refer to like parts throughout the several views, the game apparatus of the present invention includes a flat base or playing

board 1 preferably of relatively large size which may be supported on a table or the like or provided with supporting legs (not shown), and which is formed of any suitable material such as ply-wood or composition material. A suitable upstanding railing 2 of suitable material is secured to the playing board to extend around the periphery thereof. A suitable baseball diamond 3 is painted or otherwise provided on the playing surface, the diamond including representations of a home plate 4, first, second and third bases 5, 6, and 7, respectively, and a pitcher's box 8. The pitcher's box 8 in order to serve as a locating means for a ball 10, may have a slight depression therein. The ball 10, which is of a suitable size, may be of any suitable material, and if desired may be some such device as a marble.

The right, left and center fielders are represented by cages 11, 12, and 13, respectively, the catcher by a cage 14, the shortstop by a cage 15, and the first, second and third basemen by cages 16, 17, and 18, respectively. These cages, however, will be later described in detail.

Extending across the board back of the fielders 11, 12, and 13, are a plurality of cages 19 which are provided to receive the ball 10 and represents different plays when the ball is received therein. These cages are named to indicate the plays such as "Sacrifice", "2 Base hit", "Double play", and other plays. In fact, these may be of such number and so designated as to include many of the plays that arise in an actual baseball game.

In the form illustrated in the drawing, the catcher's cage and the outfields' and infielders' cages are shown to be of metal, but it is to be understood that they may be of wood or other suitable material. Furthermore, they may be of any suitable construction. In the form illustrated, which I prefer, each cage as shown in Figs. 3, 4, and 5, is comprised of a back wall 20 having ends 21, the top and front sides thereof being open. Extending across the front of the cage near the top is a bar 22, the ends of which are suitably secured to the ends 21 of the cage such as in the manner indicated in Fig. 5, and back of this bar is a pivot rod 23 from which a number of stops 24 are hingedly suspended. These stops when struck by the ball 10 swing rearwardly toward the rear wall 20 as indicated in Fig. 4, and allow the ball to enter the cage, and then swing back to their normal position to prevent the ball from rebounding through the open front. I prefer to provide the back portion of the infielders' and outfields' cages with an

opening 25 at one end to permit the ball, when it enters the cage at a certain point, to pass therethrough, thereby representing an error when the ball passes through such opening.

5 The catcher's cage 14 may be mounted on the playing board 1 back of the home plate in any suitable manner, preferably against the end rail.

The other cages may be mounted on the playing board in any suitable manner, and in the manner shown in the drawing I have provided strips 27 secured to the playing board which have upwardly offset flanges at their forward edges to provide a space for receiving rearwardly extending flanges 28 provided at the bottoms of the 15 back walls 20 of the cages as shown in Fig. 4. This provides a mounting whereby the infielders' and outfielders' cages may be shifted longitudinally to the right or left to provide different playing positions.

20 The rear play-indicating cages 19 are mounted on the board in any suitable manner adjacent the end rail, and each is provided with hinge depending stops 29 similar to the stops 24 to permit the ball 10 to enter thereinto, the tops thereof being 25 open so that the ball can be removed. These playing cages 19, as previously stated, are lettered to indicate the different plays.

A scoreboard 30 may be secured to the side rail 2 and also, for appearance, devices 31 representing 30 players' dugouts may be provided.

The game is played by two players at a time, that is, a pitcher, and a batter, although several batters may play, each taking turns. The batter and pitcher both play at the same time each 35 using a cue-like element 32 which he holds in one hand. These elements comprise a stick portion of sufficient length that the player does not have to lean over the table, preferably having an end 33 the surface of which is arcuate as shown 40 in Fig. 1. However, the end 33 may be of other suitable shapes. I have found, however, that by forming the end 33 with a curved surface the ball, by striking it at different points of the curved surface, may be made to move in different paths.

45 To play the game, the batter rests the end of the element 32 on the playing surface back of the home plate 4, and the pitcher similarly, as indicated in Figs. 1 and 2, rests the end of the element 32 that he is using on the playing surface 50 back of the ball 10, the ball 10 preferably being disposed in a depression in the pitcher's box 8. The player representing the pitcher slides the element 32 forward, striking the ball 10 and causing it to move toward the plate 4.

55 The object of the player representing the batter is to slide the element 32 that he is using and strike the ball in such manner that it will clear the infielders' and outfielders' cages and lodge in one of the play cages 19. However, should the 60 batter not strike the ball and the ball is lodged in the catcher's cage 14 this may be counted as a strike, and, similarly, should the ball clear the catcher's cage 14 this may be counted as a ball. Furthermore, if the batter does strike the ball and 65 it stops back of the foul line 34, such a play may be counted as a foul ball.

If the batter strikes the ball and returns it so that it is lodged in one of the infielders' or outfielders' cages, this may be counted as an out. 70 However, in such case, should the ball after entering one of these cages pass out through the opening 25 in the back wall, this may be counted as an error.

If the batter, for instance, should strike the ball 75 in such manner that it clears the infielders'

and outfielders' cages and becomes lodged in one of the play cages 19, such as in the "2 base hit" cage, a figure 35, representing a base runner, is deposited at second base 5. In the next play, if the batter should strike the ball and it should 5 lodge in the cage 19 marked "Single", the first runner is positioned on third base and another runner positioned on first base. On the next 10 play, if the ball is lodged in the cage 19 marked "Double play" the batter is out and either the 10 runner on first or third base is removed from the field, depending upon the particular set of rules that are formulated, and the remaining runner 15 may be advanced one base. If the man on first base is removed, then the runner on third base 15 is allowed to score a run, which may be indicated on the score board.

It is obvious that a number of rules may be formulated for playing the game and that such rules may be similar to many of those involved 20 in an actual game of baseball and it is to be understood that the foregoing plays are merely given for the purpose of illustration. Furthermore, the different plays represented by the cages 19 may be arranged in any suitable order and the different cages may be of any suitable material and of 25 any suitable construction for receiving the ball.

It is, therefore, seen that I have provided a baseball game in which both players are actively engaged at play at the same time in which the 30 players may obtain considerable exercise, and, furthermore, in which considerable skill is required to cause the ball to clear the infielders' and outfielders' cages in order to lodge in one of the play cages to accomplish a predetermined 35 play.

Furthermore, it is to be understood that the particular form of apparatus shown and described, and the particular procedure set forth, are presented for purposes of explanation and 40 illustration and that various modifications of said apparatus and procedure can be made without departing from my invention as defined in the appended claims.

What I claim is:

1. A game apparatus comprising a base having 45 a playing surface representing a baseball diamond, infielders' and outfielders' cages disposed to receive a ball manually propelled forward toward the home plate by an element in the hands of one player and manually struck back and returned by an element in the hands of another player, and a plurality of play cages disposed rearwardly of said outfielders' cages whereby when the latter player returns the ball it must clear said infielders' and outfielders' cages in order to lodge in one of said play cages to accomplish a predetermined play which depends upon the skill of the player, each of said infielders' and outfielders' cages comprising an element having a 50 back wall, side walls, an open front, an open top and a plurality of hinged stops depending across said open front.

2. A game apparatus comprising a base having 55 a playing surface representing a baseball diamond, infielders' and outfielders' cages disposed to receive a ball manually propelled forward toward the home plate by an element in the hands of one player and manually struck back and returned by an element in the hands of another player, and a plurality of play cages disposed 60 rearwardly of said outfielders' cages whereby when the latter player returns the ball it must clear said infielders' and outfielders' cages in order to lodge in one of said play cages to accom- 65

5 plish a predetermined play which depends upon the skill of the player, each of said infielders' and outfielders' cages comprising an element having a back wall, side walls, an open front, an open top and a plurality of hinged stops depending across said open front, said last mentioned element having a pivot bar extending between the upper portion of said side walls and said stops being pivoted on said bar for hinging movement 10 toward said back wall when struck by the ball.

10 3. A game apparatus comprising a base having a playing surface representing a baseball diamond, infielders' and outfielders' cages disposed to receive a ball manually propelled forward toward the home plate by an element in the hands of one player and manually struck back and returned by an element in the hands of another

5 player, and a plurality of play cages disposed rearwardly of said outfielders' cages whereby when the latter player returns the ball it must clear said infielders' and outfielders' cages in order to lodge in one of said play cages to accomplish a predetermined play which depends upon the skill of the player, each of said infielders' and outfielders' cages comprising an element mounted upon said playing surface and having a back wall, side walls, an open front, an open top, and 10 hinged stop means extending across said open front, the back wall of at least one of said elements having an opening therethrough adjacent said playing surface for the passage of the ball therethrough under certain conditions. 15
